[57] CLAIM

The ornamental design for a package for wallpaper, as shown and described.

DESCRIPTION

FIG. 1 is a perspective view of a package for wall paper showing my new design;

FIG. 2 is a front elevational view thereof;

FIG. 3 is a top plan view thereof; the bottom plan view being a mirror image thereof;

FIG. 4 is a right side elevational view thereof; undisclosed in FIG. 1;

FIG. 5 is a sectional plan view thereof; taken along line 5—5 of FIG. 1; and,

FIG. 6 is a sectional plan view thereof; taken along line 6—6 of FIG. 1.

The rear elevational view is plain and unornamented.

FIG. 1.

FIG. 2.

FIG. 3.

FIG. 4.

FIG. 5.

FIG. 6.
